UNITED STATES PATENT OFFICE.

FRED W. COOLEY, OF MINNEAPOLIS, MINNESOTA, ASSIGNOR OF TWO-
THIRDS TO GEORGE T. HONSTAIN, OF MINNEAPOLIS, MINNESOTA.

FIREPROOF BUILDING.

SPECIFICATION forming part of Letters Patent No. 707,210, dated August 19, 1902.

Application filed December 13, 1901. Serial No. 85,726. (No model.)

To all whom it may concern:

Be it known that I, FRED W. COOLEY, a citizen of the United States, residing at Minneapolis, in the county of Hennepin and State of Minnesota, have invented certain new and useful Improvements in Fireproof Buildings; and I do hereby declare the following to be a full, clear, and exact description of the invention, such as will enable others skilled in the art to which it appertains to make and use the same.

My present invention relates to fireproof buildings or structures of the type wherein the walls are constructed of tile blocks and interposed metal bars, and has for its especial object to improve the construction of grain-storage bins or buildings.

To the above ends the invention consists of the novel devices and combinations of devices hereinafter described, and defined in the claims.

The invention is illustrated in the accompanying drawings, wherein like characters indicate like parts throughout the several views.

Figure 1 is a diagrammatic plan of a section of a building made up of bins and embodying my invention. Fig. 2 is a vertical section on the line $x^2 x^2$ of Fig. 1, some parts being broken away. Fig. 3 is a skeleton view, partly in side elevation and partly in section, on the line $x^3 x^3$ of Fig. 1. Fig. 4 is a horizontal section on the line $x^4 x^4$ of Fig. 2, some parts being removed and others being broken away. Fig. 5 is a vertical section on the line $x^5 x^5$ of Fig. 4. Fig. 6 is a section approximately on the line $x^6 x^6$ of Fig. 4, parts being broken away. Fig. 7 is a transverse vertical section taken on the line $x^7 x^7$ of Fig. 5. Fig. 8 is a plan view of one of the so-called "anchoring hooks or devices". Fig. 9 is a side elevation of one of the said anchoring-hooks. Fig. 10 is a horizontal section on the line $x^{10} x^{10}$ of Fig. 2, some parts being broken away. Fig. 11 is a vertical section on the line $x^{11} x^{11}$ of Fig. 10.

The walls are made up of tile blocks 1 and interposed horizontally-extended iron or steel bars 2. The bars 2 are preferably of flat metal, and they are laid double or one on

top of the other with their joints overlapped. The tile blocks may be of any desired size; but for ordinary grain-elevator construction they will usually range from about twelve to eighteen inches in height.

One of the problems which had to be solved in the practical construction of buildings of this character has been to provide suitable devices or means for securely anchoring the tile blocks to the flat metal bars, and this I have solved in my present invention by the use of anchoring devices which are best afforded by hooked wire sections adapted to overlap the said bars and to be embedded in the cement. The cement is thus anchored to the said bars, and the tile blocks are of course securely held by the cement. These anchoring-hooks 3 are best shown in Figs. 8 and 9 in detail and in Fig. 4 as applied in working position. As shown, they are of V-shaped form, having hooked ends 3^a, which are adapted to engage over the edges of the overlapped bars 2 and to project inward thereunder. Cement in the drawings is indicated by the character z . The cement laid on top and under the bottom of the overlapped bars 2 is anchored to the said anchoring-hooks 3 and by them is securely anchored to the said bars. Of course the cement will of itself tend to adhere to these iron bars; but this adhesion alone without the use of the anchoring devices has been found not to be sufficient, especially where flat iron is used. The anchoring-hooks when embedded in the cement further serve to lock the overlapped bars 2 together and against lateral movements. The said anchoring devices may of course take various forms; but the form illustrated in the drawings is of small cost and has many advantages over all other forms which now occur to me.

The construction of a corner where four bins adjoin is best illustrated in Figs. 2, 4, 5, 6, 10, and 11. At these corners the upper bars 2 of the one wall abut or join, while the coöperating lower bars extend continuous or through the joint. The bars of the intersecting wall are just reversely arranged—that is, the under bars abut, while the upper bars extend through the joint. To form col-

umns at the corners, I use vertically-disposed angle-irons 4, which are placed with their right-angle corners one in each of the four corners formed by the intersecting bars 2. 5 These columns 4 are securely bound together by binding-straps 5, (best shown in Figs. 4 and 5.) the ends of which are bent over the flanges of said columns, and thus hold the said columns tightly drawn against the adjacent 10 edges of the bars 2. These binding-straps 5 are preferably arranged in pairs, the one pair extending just above the other and both pairs extending above the corresponding bars 2, as best shown in Fig. 5. The rectangular space 15 left between the binding-straps 5 in a horizontal direction and between the underlying and overlying bars 2 is filled in by the tile block 6, which is rectangular, except that it is notched at its corners, as indicated at 6^a. 20 In line with the notches 6^a of said tile blocks the bars 2 are provided with notches 2^a, as best shown in Fig. 10. Through these notches 2^a lock-bolts 7 are passed. These lock-bolts 7 may extend from top to bottom of the 25 column or corner or may be afforded by short bolts or sections applied independently at each joint. In this manner the bars 2 are locked together. More specifically stated, the bar which extends through the joint serves 30 to lock together the ends of the abutting bars. The hollow tile blocks 6 are advisably filled with cement, so that they form a solid column. Cement is of course also placed around the said corner-tiles 6 and between the ends 35 of the same and the bars 2. Where the bins are of considerable size, angle-columns 4, arranged in groups of four, as indicated in Figs. 1, 10, and 11, are run up the central or intermediate portions of the bin-walls. The 40 positively-located pairs of these angle-columns 4 are tied together by horizontally-extended truss bars or rods 8, which are bolted or otherwise secured to the flanges thereof, preferably by bolts 9. Otherwise stated, the intermediate 45 columns rigidly connect the intermediate portions of all of the horizontal bars of the particular wall, or, more properly speaking, are anchored to all thereof. The tie-bars then being connected to these intermediate 50 columns are by them connected to the metal wall-bars, so that all thereof are reinforced by said tie bars or rods. The truss bars or rods 8 are thus extended in pairs across the bins to connect the opposite walls 55 thereof. Normally the bars 8, which constitute a pair, extend parallel; but to tighten the same, and thus to draw more firmly on the side walls, they are themselves drawn together at their central or intermediate portions, preferably by short nutted bolts 10, passed therethrough, as best shown in Fig. 1. These truss-bars 8 are placed at suitable intervals in a vertical direction and should be spaced more closely near the bottom than at the 60 top of the bin. Their exact disposition and strength are of course a matter to be determined by an engineer or architect.

The term "tile blocks" has been generally used throughout the specification and in the claims; but it will of course be understood that bricks or solid blocks would be their mechanical equivalent, so far as the novel features of my present invention are concerned. It will also be understood that the invention above specifically described is capable of many modifications within the scope of my invention as herein set forth and claimed.

What I claim, and desire to secure by Letters Patent of the United States, is as follows:

1. In a fireproof wall, the combination with 80 tile blocks and interposed metal bars, of anchoring devices locked to said bars and embedded in the cement interposed between said bars and tile blocks.

2. In a fireproof wall, the combination with 85 tile blocks and interposed metal bars, of anchoring devices overlapping the edges of said bars and embedded in the cement interposed between said bars and tile blocks.

3. In a fireproof wall, the combination with 90 tile blocks and interposed metal bars, of the anchoring-hooks 3 embedded in the cement interposed between the said bars and tile blocks and provided with the hooked ends 3^a which overlap the edges of said bars.

4. In a fireproof wall, the combination with tile blocks and metal bars laid double and interposed between the layers of tile blocks, of anchoring devices embedded in the cement interposed between said tile blocks and bars 100 and engaging over the edges of said bars to prevent lateral movements of the one bar with respect to the other, substantially as described.

5. In a fireproof wall, the combination with 105 the tile blocks and metal bars laid double and interposed between said layers of tile blocks, of the anchoring-hooks 3 embedded in the cement interposed between said tile blocks and metal bars and provided with hooked 110 ends 3^a which engage over the edges of said bars and hold the same against lateral movements, one with respect to the other.

6. In a fireproof structure, the combination with wall-tiles and interposed metal bars 115 which bars overlap at the corners of the bin, of metal columns placed in the corners formed at the junction of said walls, and devices for tying the said columns together, substantially as described.

7. In a fireproof structure, the combination with wall-tiles and interposed metal bars overlapped at the corners of the bins, of metal angle-columns placed in the corners at the junctions of said walls, and metal tie-straps 125 connecting the opposite angle-columns and with their ends bent to embrace the flanges thereof, substantially as described.

8. In a fireproof structure, the combination with wall-tiles and interposed metal bars 130 overlapped at the corners of the bins, of the angle-iron columns 4 placed in the corners at the junctions of the walls, and the tie-straps 5 connecting the opposite angle-col-

umns and having their ends bent over the flanges thereof, substantially as described.

9. In a fireproof structure, the combination with the wall-tiles 1 and interposed metal bars 2 the latter being overlapped at the corners of the bins, the corner-tiles 6 placed at the corners of the bins, the angle-columns 4 placed in the corners formed by adjoining walls, and the tie-straps 5 embracing said corner-tiles and with their ends bent around the flanges of opposite angle-columns, substantially as described.

10. In a fireproof structure, the combination with wall-tiles of the interposed and overlapped metal bars 2 provided at the corners of the bins with notches 2^a and lock-bolts placed within said notches 2^a for interlocking the parts, substantially as described.

11. The combination with the walls of a bin or similar structure, of truss rods or bars arranged in approximately parallel pairs connecting the opposite sides thereof, and means for drawing the central portions of said truss- rods together to tighten the same, substantially as described.

12. The combination with the walls of a rectangular bin or structure made up of tile blocks and interposed metal bars, of intermediate columns reinforcing the walls of said bin and laterally-spaced metal bars or rods connecting opposite members of said intermediate columns which tie bars or rods are arranged in pairs and are drawn together

at their intermediate portions, substantially as described.

35

13. The combination with a bin or similar structure, the walls of which are made up of tile blocks and interposed metal bars or beams, of columns applied to the intermediate portions of said interposed bars or beams, and tie bars or rods connecting the opposite or distant intermediate columns.

40

14. The combination with the walls of a rectangular bin or similar structure made up of layers of tile blocks and interposed metal bars or beams, of intermediate columns arranged in groups of four positioned in pairs on the opposite sides of said interposed bars, and pairs of tie bars or rods connecting opposite pairs of said intermediate columns, substantially as described.

45

15. The combination in a fireproof wall, of layers of tile blocks and interposed and overlapped metal bars provided with coincident notches, and lock-pins placed in the said coincident notches whereby the said overlapped bars are locked against endwise movements, one upon the other, substantially as described.

50

In testimony whereof I affix my signature in presence of two witnesses.

FRED W. COOLEY.
